UNDERGARMENT

Henry Jean, Hamilton, Ontario, Canada, assignor
to Leo J. Layden, Hamilton, Ontario, Canada

Application June 2, 1937, Serial No. 146,029
In Canada June 3, 1936

5 Claims. (Cl. 2—224)

The principal objects of this invention are to provide a neat and comfortable fitting trunk garment which will fit snugly and will form a garment presenting a suitable and comfortable support.

The principal features of the invention consist in the novel form of trunk having a snug-fitting waistband and snug-fitting leg bands with a reinforced center portion provided with a fly-closed opening arranged above a medially arranged pleat.

In the accompanying drawing, Figure 1 is a front elevational view of my improved garment.

Figure 2 is a rear elevational view. 15 Figure 3 is an enlarged perspective view of the garment and Figure 4 is an enlarged diagrammatic detail view showing the structure of the front panel.

In the construction herein shown, the rear panel 1 forms about half of the upper portion of the trunk-surrounding band tapering downwardly to a narrow crotch portion 2. To the converging edges 3 there are secured the side portions 4 which are joined to the front panel which is made up of a plurality of sections. The upper section 5, which is of converging form, is formed of a double thickness of material seamed at its side edges to the portions 4 and at its top to the waistband 6.

30 An intermediate or fly section 7 formed of two doubled pieces of cloth are arranged to overlap each other in the manner particularly shown in Figure 4 and the upper edges are secured to the bottom edge of the upper front section 5, the doubled edges overlapping in a wide central overlap.

A lower or crotch section 8 also formed of a doubled thickness of material, is formed with a central box-pleat 9 and the upper edge is stitched 40 to the bottom edge of the fly section 7, the box-pleat portion being preferably interposed between or abutted against the lower edge portion of the fly section 1.

The bottom edge of the pleated section 8 is 45 butted and stitched to the narrow edge or end of the crotch portion 2 of the back panel.

All of the seams of this garment are formed by an overcast elastic stitch which forms a secure binding of abutting or overlapping edges of fabric.

50 The back panel and side portions 4 are preferably formed of a single thickness of material, whereas the several sections of the front panel are preferably formed of doubled textile fabric. The front panel thus has less longitudinal elastic-
ity than has the back panel, but the wales of the

knitted fabric from which both front, side and back panels are made, all extend downwardly from the elastic waistband, thus permitting ample lateral stretch.

A doubled fabric is stitched to the bottom edges 6 of the several panels to form elastic leg bands which fit snugly around the limbs of the wearer.

It will be appreciated that the double thickness of the upper front panel member 5 will form a substantially non-stretchable lengthwise support 10 for the fly section 7, consequently the fly will normally be maintained closed, so also the doubled or partly-quadrupled section of the box-pleated portion of the lower portion of the front panel, will have ample room for lateral distention without any appreciable longitudinal stretch.

A garment constructed as described will fit snugly against the front of the body and the back panel and side sections will readily stretch around the hips, thus producing a very comfortable garment.

What I claim as my invention is:—

1. A man's undergarment having a center front section composed of triple panels disposed in series between the waistband and the lower crotch 25 extremity, the intermediate panel having a fly opening extending the full distance between the adjacent edges of the upper and lower panels and reinforced at the ends by connection therewith, the lower panel having a central vertical box 30 pleat continuing downward directly from the lower extremity of the fly opening.

2. A garment as claimed in claim 1 in which said intermediate panel comprises two separate doubled sections of knitted fabric of substantially 35 identical size and shape disposed with their doubled edges substantially parallelly overlapped and stitched at the ends to the respective adjacent edges of the upper and lower panels whereby a reinforced fly of four-ply is provided free of 40 separate binding at the edges.

3. A man's undergarment having a waistband, a center panel secured to said waistband and formed of a double thickness of knitted fabric with the wales extending downwardly, a pair of 45 doubled pieces of fabric with the wales extending downwardly secured to the bottom edge of said front panel with the doubled edges overlapping forming a fly opening, and a lower front section formed of doubled knitted material with the 50 wales extending longitudinally and having its upper edge secured to the bottom edge of the fly opening portion.

4. A man's undergarment having a waistband, a center panel secured to said waistband and 55

- formed of a double thickness of knitted fabric with the wales extending downwardly, a pair of doubled pieces of fabric with the wales extending downwardly secured to the bottom edge of said front panel with the doubled edges overlapping forming a fly opening, and a lower front section formed of doubled knitted material with the wales extending longitudinally and having its upper edge secured to the bottom edge of the fly opening portion with the center part thereof formed into a box pleat.
5. A man's garment having a waistband, a back panel extending downwardly from said waist-

band and converging inwardly to a crotch formation and having the wales extending downwardly from the waistband, side panels connected to said waistband and to said back panel also having the wales extending downwardly, and a front panel connected centrally to the waistband and diagonally to the side panels and being formed of doubled material with the wales extending downwardly, the center portion having a vertically arranged fly therein and a longitudinally arranged box pleat therebelow extending to the crotch portion of the back panel.
